I. F. BYRNES

HIGH FREQUENCY SIGNALING SYSTEM

Filed May 11, 1925

Inventor:
Irving F. Byrnes,
by Alexander S. Lunt,
His Attorney.

UNITED STATES PATENT OFFICE.

IRVING F. BYRNES, OF SCHENECTADY, NEW YORK, ASSIGNOR TO GENERAL ELECTRIC COMPANY, A CORPORATION OF NEW YORK.

HIGH-FREQUENCY SIGNALING SYSTEM.

Application filed May 11, 1925. Serial No. 29,304.

My present invention relates to signaling systems adapted for duplex operation, and more particularly to high frequency signaling systems adapted for telephone communication.

One method which has been proposed for permitting of duplex communication by the use of a single high frequency for transmission in both directions consists in the provision of a transmitting apparatus which is operative only when the signaling potential is impressed thereon and which will supply no high frequency current to the communication circuit at other times.

The object of my invention is to provide a transmitting system which will be operative only when a signaling potential is applied thereto.

The novel features which I believe to be characteristic of my invention are pointed out with particularity in the appended claims; my invention itself, however, both as to its organization and method of operation will best be understood by reference to the following description taken in connection with the accompanying drawing in which I have shown diagrammatically one circuit organization which may be used in carrying my invention into effect.

I have indicated in the drawing the application of my invention to a transmitting system adapted for duplex radio telephone communication through the medium of an antenna 1. The receiving apparatus which may be used with the system illustrated may also be connected to the antenna 1, but apparatus for this purpose is not indicated as it forms no part of my present invention. A suitable apparatus for this purpose is described and claimed in a co-pending application of Emmet F. Carter, Serial No. 752,243, filed November 25, 1924.

The transmitting apparatus illustrated comprises a three-electrode electron discharge tube 2, which serves as an oscillation generator, an intermediate amplifying tube 3, which serves to amplify oscillations produced by tube 2, a power amplifying tube 4, which serves to amplify oscillations delivered by amplifying tube 3, and modulating tube 5, which serves to modulate the amplified oscillations supplied by tube 4 to the antenna 1, and a control tube 6 for controlling the operation of the intermediate am-

plifying tube 3. The necessary potentials required for operating the plate circuits of the tube equipment are supplied by a source of potential 7, which is indicated as a battery, but which may be any convenient source adapted to supply the different potentials required for the operation of the different tubes.

Intermediate amplifying tube 3 is connected in series with the plate circuit of control tube 6. The grid of tube 6 is biased by means of the battery 8 to a negative potential of such value that under normal conditions substantially no current will flow in the plate circuits of tubes 6 and 3, and hence no high frequency currents will be supplied to the antenna 1. Current produced in the local circuit of microphone 9 is supplied by means of the secondary transformer windings 10 and 11 to the grid circuit of the modulator tube 5 and to the grid circuit of control tube 6. When an audio frequency signaling potential is thus impressed on the grid circuit of control tube 6 the grid potential becomes less negative, permitting current to flow in the plate circuit of intermediate amplifier 3. High frequency oscillations produced by the tube 2 are then supplied through the coupling condenser 12 to the grid of amplifier 3, and amplified. The amplified oscillations are supplied by coupling condenser 13 to the grid of the power amplifier tube 4. The amplified oscillations set up in the plate or output circuit of tube 4 are modulated by the action of tube 5 in a well known manner, and thus modulated high frequency oscillations are supplied to the antenna 1 as long as signaling current is supplied by the microphone 9. As soon as the signaling current ceases current through tubes 6 and 3 is automatically reduced to a substantially zero value and no high frequency current will be supplied to the antenna 1. Thus, there will be no interference with reception upon the antenna 1.

What I claim as new and desire to secure by Letters Patent of the United States, is:—

1. A transmitting apparatus for a high frequency signaling system comprising a source of high frequency oscillations, an amplifying tube having a plate circuit which includes an impedance of such value that normally substantially no current will flow

- therein, means for supplying high frequency oscillations from said source to the grid of said amplifier tube, means for lowering said impedance in response to signaling potential sufficiently to permit current to flow in the plate circuit of the amplifier, and means acting independently of said impedance for modulating the amplified high frequency currents.
- 10 2. A transmitting apparatus for a high frequency signaling system comprising a source of high frequency oscillations, an electron discharge amplifier having a plate circuit which includes an impedance consisting of an electron discharge device which is so adjusted that normally substantially no current will flow in the plate circuit of the amplifier, means for supplying high frequency oscillations from said source to the 20 grid of said amplifier, means responsive to a signaling potential for varying the adjustment of said electron discharge device to permit current to flow in the plate circuit of the amplifier, and means acting independently of said impedance for modulating the amplified high frequency currents.
- 30 3. A transmitting apparatus for a high frequency signaling system comprising a source of high frequency oscillations, an electron discharge amplifier having included in its plate circuit a three-electrode electron discharge device having its grid potential normally of such value that substantially no current will flow in the plate circuit of the 35 amplifier, means for supplying high frequency oscillations from said source to the grid of said amplifier, means responsive to a signaling potential for permitting current to flow in the plate circuit of the amplifier and means acting independently of said

three-electrode device for modulating the amplified high frequency oscillations.

4. A transmitting apparatus for a high frequency signaling system comprising a source of high frequency oscillations, an electron discharge amplifier having included in its plate circuit a three-electrode electron discharge device having its grid potential normally of such value that substantially no current will flow in the plate circuit of the 50 oscillator, means for supplying high frequency oscillations from said source to the grid of said amplifier, means for impressing a signaling potential upon the grid of the electron discharge device and thereby permitting current to flow in the plate circuit of the 55 amplifier, and means acting independently of said three-electrode device for modulating the amplified high frequency oscillations.

60 5. The combination in a high frequency signaling system of a transmitting apparatus comprising a source of high frequency oscillations, an electron discharge amplifier for amplifying oscillations produced by said source, a three-electrode electron discharge control device for controlling the operation of said amplifier, a three-electrode electron discharge modulator for modulating the amplified oscillations, and means for simultaneously impressing a signaling potential upon the grids of said control device and said modulator for rendering the amplifier operative to amplify high frequency oscillations supplied by said source and modulating the amplified oscillations.

70 In witness whereof, I have hereunto set my hand this 9th day of May, 1925.

75 IRVING F. BYRNES.
